TIGHTENING DEVICE FOR TYPE

Robert Strahm, Bern, Switzerland

Application December 2, 1932, Serial No. 645,391
In Switzerland July 16, 1932

6 Claims. (Cl. 101—404)

My invention relates to tightening devices for type.

For holding type together the same has heretofore been simply tied with cords. As the defects attaching to this mode of tying are serious, because the cords become loose and have to be removed for printing in a machine, it has been proposed to use for this purpose frames or furniture which, however, on account of rigidity are used only for certain sizes of type and, therefore, have only a restricted use. It has also been proposed to use bands instead of cords, and to connect their ends together by means of pins.

These well-known tightening devices do not permit of the type being embraced sufficiently tightly for not only holding the type together but also preventing so-called "picks", i. e. rising of the space-lines and like blind material in the machine during the printing operation.

According to the present invention, there is provided a type-tightening or tensioning device, comprising a band for encircling the type, which device is characterized by a winding mandrel or spindle for the band which mandrel or spindle can be held against rotation by a ratchet wheel and is held in two discs rotatably inserted from outside into the webs or limbs of a bar or rail serving as a column strip of furniture, of which discs one is formed on the outside with ratchet teeth, adapted to be automatically engaged by a toothed detent which is elastically displaceable on said bar or rail, the arrangement being such that the space between the limbs of the bar or rail is left quite free for the passage of the metal band.

According to the present invention, the mandrel is formed by two adjacent wires which extend beyond the toothed disc and are rigidly connected together by a middle piece so that they can be used as a pin for receiving a key for turning the mandrel, and the discs are held in their bearings by the middle piece.

Preferably, the winding mandrel is arranged at one end of the rail or bar, at which end the rear wall of the latter is removed.

One embodiment of the invention is diagrammatically illustrated by way of example in the accompanying drawing, wherein:

Figure 1 is a vertical sectional elevation showing one form of type tightening device embodying the invention.

Figure 2 is a horizontal section thereof, partly broken away,

Figure 3 is a detail plan view, and

Figure 4 is a section taken on the line IV—IV in Fig. 3.

Like reference characters designate like parts in all the views.

As shown on the drawing, a frame in the form 60 of a rail or bar 1 of U-section, which can be used as column furniture, has its rear wall removed at one end leaving the side webs free. A winding mandrel 2 for winding up and tightening a metal band 3 to encircle the type is rotatably mounted in the webs at that end of the rail. This mandrel comprises two parallel heavy wires of round section, so that sharp edges which might crease or crack the band are avoided. At their lower ends the wires are rigidly connected together by a disc 8 having a rabbeted or grooved periphery. This disc 8 is rotatably inserted from below, i. e. outside, into a circular recess 9 in the lower web of the U-shaped frame 1. The upper ends of the wires forming the 75 mandrel 2 extend through a disc 10 which has its periphery rabbeted and has its reduced portion rotatably inserted from above, i. e. outside, into the upper web of the U-shaped frame 1. The upper ends of the wires forming the 80 mandrel 2 extend upwards beyond the disc 10 and by a distance piece or spacer 12 being welded to them, are given the shape of a flattened pin, over which a hollow key can be placed for turning the mandrel 2.

The wires 2 are thus securely and rigidly connected together by the spacer 12 and the discs 8 and 10 so that they cannot be twisted even when a severe torque is applied to the mandrel. Further, the distance between the discs 8 and 90 10 is determined very simply by the distance piece 12, so that the discs are reliably held in their seats in the webs of frame, 1.

A slot 5 for the insertion of the end of the band to be wound up on the mandrel 2 is constituted by a space between the two wires. The other end of the band is preferably led round the rear or bottom wall of the frame 1 and inserted into a vertical slit 1' in the rear wall.

The portion of the disc 10 of larger diameter 100 is provided with ratchet teeth 11, with which engages a relatively broad bolt or detent 13 having corresponding ratchet teeth at its free front end. The other or rear end is bent upwards (Fig. 1) and is guided to move on the upper 105 limb or web of frame 1 by a forwardly extending pin 14 which enters into a hole in the upwardly bent end of detent 13. The latter having the form of a blade is also guided by a pin 15 carried by the upper web of frame 1 and ex- 110

tending through a slot 16 in the detent. A spring 17 surrounding the pin 14 holds the detent 13 in engagement with the teeth 11 of the disc 10.

The employment of a broad detent having several teeth enables the use of a thin disc 10 and detent, which is very important for enabling a broad band to be used, since no part of the tightening device must project beyond the furniture of the type.

- 10 One advantage of the above described improved type-tightening device as compared with the old devices is that between the webs of the U-shaped frame of the device there are no parts which obstruct the band or binder while being wound on the mandrel. Therefore, a considerably thinner and broader band can be used than in the known tensioning devices, which results in an improved binding action, and yet the device can be made very small. Because of the employment 20 of a broad metal band its thickness may be equal to the usual unit of change of size of a type, i. e. half a point, that is 0.18 mm., so that when the herein described band-tensioning device is used the sizes of the composed type may be kept within 25 in the usual limits, which is not the case with narrow bands and those of textile fabric when several sets of type are to be put in the press and a predetermined size for all the sets must be maintained.
- 30 Another advantage is that as the mandrel 2 is situated at the end of the frame 1 of U-section and the rear wall thereof is removed at that end, the mandrel is easily accessible for the insertion of the metal band, and it is possible to employ a narrow frame of a thickness equal to a standard column stick and yet wind up a predetermined or sufficient length of band to enable making any corrections in the type, e. g. removal of an entire line, which necessitates 40 shortening the band.

Again, when the band is wound on the mandrel, it is not bent around any sharp edges which under some circumstances might cause cracks in the band. Also, the improved device is simple 45 and, therefore, can be made at a low cost.

Since, as mentioned above, the metal band, because of its thinness, projects very slightly laterally from the type, and as the band is broad a large number of sets of type each provided with 50 the herein described tensioning device can be secured in a printing press, the frame 1 being suitable for use as part of a column strip. On the other hand, the device enables the matter

to be readily loosened in the press for the purpose of making corrections, since the locking device of the mandrel is readily accessible.

I claim:

1. A band tensioning device of the type described comprising in combination a frame of U-section adapted to serve as furniture for type, two discs journaled one in the outer face of each web of the frame, one of which discs has a toothed periphery, a mandrel carried by said discs, a spring-controlled detent movable on said frame and engaging the toothed disc, the space between said webs being unoccupied except by said mandrel and being left free for the band. 80

2. A band-tensioning device of the type described comprising in combination a frame or bar of U-section adapted to serve as a column strip of furniture for type, two discs journaled one in the outer face of each web of the frame, one of which discs has a toothed periphery, a mandrel comprising two parallel wires securely carried by said discs and extending beyond the outer face of one of them, and a distance piece rigidly connected to said wires at their outer end, which end serves for receiving a key for rotating the 100 mandrel, and a spring-controlled detent slideable on said frame and engaging the toothed disc. 90

3. A band-tensioning device of the character described according to claim 1, characterized in that the mandrel is of substantially oval cross- 105 section and has a longitudinal slot for receiving one end of the band.

4. A band-tensioning device according to claim 1, wherein the mandrel comprises two wires, each of circular cross-section, spaced apart between 110 their ends to form a slot for receiving one end of the band.

5. A band-tensioning device according to claim 1, wherein the detent has the form of a blade having a plurality of teeth at one end for engaging the teeth of the disc. 115

6. A band tensioning device of the kind described, comprising a substantially U-shaped frame adapted to serve as furniture for type, two disks rotatably journaled one each in the parallel webs of said frame, a slotted mandrel operatively associated with said disks so as to rotate therewith, a portion of the rear wall of said frame between said webs being removed permitting an open space to be formed capable of receiving the roll of band while being wound on 120 said mandrel. 125
